ELECTRICAL SWITCH ASSEMBLY

Dwayne A. MacDonald, Santa Ana, Calif.
(1921 Maryglade Drive, Grafton, Wis. 53024)

Filed May 5, 1972, Ser. No. 250,856

Term of patent 14 years

Int. Cl. D13—03

U.S. Cl. D26—13 R

FIG. 1

FIG. 2

FIG. 3

FIG. 4

FIG. 5

FIG. 1 is a perspective view of the electrical switch assembly of this invention;

FIG. 2 is a front elevational view of the electrical switch assembly;

FIG. 3 is a right side elevational view of said electrical switch assembly;

FIG. 4 is a rear elevational view of said electrical switch assembly; and

FIG. 5 is a bottom plan view of said electrical switch assembly.

I claim:

The ornamental design for an electrical switch assembly, as shown.
